Inventor*

United States Patent Office.

SAMUEL A. BLAKE, OF MILFORD, CONNECTICUT.

Design No. 2,941, dated March 3, 1868.

DESIGN FOR AN IMITATION BRAID FOR BONNETS.

The Schedule referred to in these Letters Patent and making part of the same.

TO ALL WHOM IT MAY CONCERN:

Be it known that I, SAMUEL A. BLAKE, of Milford, in the county of New Haven, and State of Connecticut, have invented a new Design for Imitation Braid for Bonnets, &c.; and I do hereby declare the following, when taken in connection with the accompanying drawing, and the letters of reference marked thereon, to be a full, clear, and exact description of the same, and which said drawing constitutes part of this specification, and represents a view of the central portion of the top of a hat.

This invention relates to a design for that class of hats, bonnets, or other coverings for the head, which are made in imitation of straw-goods, and are formed by cutting the design into proper dies, and pressing the material therein; and the invention consists in the peculiar form or configuration representing the braid, and which said design, although it may be impossible to produce a braid of exactly the same design, yet it represents or has the appearance of a braid of difficult fabrication, and is fully shown in the accompanying illustration.

What I claim as new, and desire to secure by Letters Patent, is—

The peculiar configuration or design for an imitation braid, as clearly shown and defined in the accompanying drawing.

SAMUEL A. BLAKE,

Witnesses:

A. J. TIBBITS,

J. H. SHUMWAY.
